Inventors:

S. W. Pearsall

W. L. Pearsall.

UNITED STATES PATENT OFFICE.

S. W. PEARSALL AND W. L. PEARSALL, OF NEW YORK, N. Y.

PLATE-VISE.

Specification of Letters Patent No. 22,822, dated February 1, 1859.

To all whom it may concern:

Be it known that we, SYLVESTER W. PEARSALL and WASHINGTON L. PEARSALL, of the city and State of New York, have invented, 5 made, and applied to use certain new and useful Improvements in Plate Vises or Holders for Photographs, &c.; and we do hereby declare that the following is a full, 10 clear, and exact description of the construction and operation of the same, reference being had to the annexed drawing, making part of this specification, wherein—

Figure 1, is a plan and Fig. 2, is a vertical section of our said plate vise.

15 Similar letters denote the same parts.

Holders or vises for the glass plates that are used in photography, and for receiving the plate holders while being buffed for daguerreotyping, have been variously constructed, with sliding, changeable and adjustable jaws, retained in position for the particular sized plate, by various devices such as pawls, notches or clamps, etc.

Our invention therefore does not relate 25 broadly to adjustable vise or holder adapted to receive various sizes of plates, but our invention consists in a peculiar spring clamping jaw and releasing lever, combined with an adjustable sliding jaw fitted to move on 30 a rod and retained by a thumb-screw. These jaws are so mounted on a vertical stud that they can be turned around horizontally into the desired position and held firmly; and said jaws are provided with lips or clamping pieces formed of hard india rubber or 35 gutta percha.

In the drawing *a*, is a socket to be secured to the bench or table receiving a vertical gudgeon *b*, from the stock *c*; and *d*, is a 40 rod extending from the said stock *c*, and formed with a key or feather, as seen in Fig. 3, to guide the movable jaw *e*, that sets over and slides on said rod *d*, and is secured by the set screw *f*.

45 *g* is the clamping jaw attached by the joint pieces and center pin *h*, to the stock *c*.

i is a spring tending to throw the jaw *g* toward the movable jaw *e*, and *f* is a lever formed on or attached to said jaw *e*, by the 50 depressing of which the jaw *e*, will be partially turned back.

1, and 2, are the jaws adapted to receive

a photographic glass or plate, and formed of hard india rubber or gutta percha, 55 screwed or otherwise secured onto the respective jaws of the holder. By this character of jaw pieces the danger of cracking the glass is materially lessened, because a more even bearing can be obtained and the same is not affected by corrosion from chemicals, 60 or liable to become dirty and soil the plates as in the ordinary metal and wood plate vises.

The manner of using this vise is as follows: Lay one edge of the glass or other 65 plate against the jaw *g*, slide said jaw *e*, lengthwise of the rod until the other edge of the plate comes almost to the holding edge *l*, of the jaw *g*, then press on the lever *f* which throws said jaw *g*, back, the plate 70 drops down and is secured in the rabbet of the jaws by the spring *i*, acting on said jaw *g*, which thus clamps or releases the plate by a rocking motion given by the joint operation of the spring *i*, and pressure on the 75 lever *f*. Our plate vise is thus adapted to any size of plate, holds the same firmly by jaws not subject to oxidation or injury to the plate, and the whole apparatus can be turned around horizontally, so as to be in 80 the most convenient position, on the gudgeon *b*, which, with the other parts, is held firmly by the screw *h*.

What we claim as our invention and desire to secure by Letters Patent is— 85

1. The spring rocking jaw and lever *f*, in combination with the movable jaw *e*, substantially as described and shown.

2. We also claim the jaw pieces or facings of hard rubber or gutta percha for the purposes and as specified. 90

3. And we claim the arrangement of the rod *d*, stock *c*, and gudgeon *b*, entering the socket *a* and having the set screw *h* by which the apparatus is retained in position 95 horizontally as specified.

In witness whereof we have hereunto set our signatures this twenty ninth day of December 1858.

S. W. PEARSALL.
W. L. PEARSALL.
